PORK SIDE STRETCHER

Harry F. Lee, Springfield, Ohio

Application January 20, 1938, Serial No. 185,793

Renewed February 9, 1940

6 Claims. (Cl. 17—44)

This invention relates to a means for and method of stretching, sizing and shaping sides of pork which are to be made into bacon.

The main objects of this invention are to provide means whereby a pork side may be cut of larger size than heretofore and then reduced in width by increasing its length, with the result that more poundage of meat may be incorporated into the bacon side than heretofore and still have the bacon side of such width as to be sliced in a standard slicing machine; to provide means for squaring up a bacon side to rectangular shape free from wrinkles; to provide an improved means for subjecting the pork side to a continuous tension during the smoking or curing operation; to provide improved means for holding the pork side while affixing the stretching means thereto, and to provide an improved pork side stretcher which is readily adjustable to accommodate sides of widely varying length.

An illustrative embodiment of this invention is shown in the accompanying drawing, in which:

Figure 1 is a view in perspective of a pork side before stretching;

Fig. 2 is a view showing how the pork side is compressed in a sloping-sided trough for reducing its width and holding it securely while affixing the stretcher thereto;

Fig. 3 is a vertical longitudinal sectional view taken through the compressing trough and showing the stretcher affixed to the opposite ends of the pork side;

Fig. 4 is a view similar to Fig. 3 but with the stretcher elongated to lengthen the side of pork;

Fig. 5 is an enlarged transverse sectional view taken on the line 5—5 of Fig. 4;

Fig. 6 is a view in perspective of the improved pork side stretcher with the toggle linkage actuated to extended position;

Fig. 7 is a view in perspective of one end of a modified form of stretcher which is adapted to exert a constant stretching action on the pork side;

Fig. 8 is a plan view showing in dotted outline the original shape of a pork side, and in full lines the same pork side after being stretched;

Fig. 9 is a similar view showing how a pork side with one edge longer than the other is squared up to rectangular shape by the stretching action.

It has long been recognized as highly desirable to have pork sides which are used for bacon, squared up in rectangular form, flat and free from wrinkles, and not more than 9 inches in

width. Insofar as the width is concerned, it very often happens that the butcher has a pork side which is considerably more than 9 inches in width, but due to the fact that there are in existence a very large number of bacon slicing machines which are so limited in size that they will not take a bacon side more than 9 inches in width, it is necessary for the butcher to cut the pork side much smaller than the material available, with the result that several pounds of meat, which otherwise could be incorporated in the relatively high priced bacon side, are used for other purposes and a much lower price realized from it. It is, therefore, highly desirable to be able to utilize the large amount of poundage in some pork sides to be sold as bacon. However, the over-all width of the bacon side must not be greater than the capacity of the slicing machines.

Many devices have been heretofore made which attempt to produce a flat, wrinkle-free, squared-up rectangular bacon side. It is well understood, of course, that pork sides are soaked in salt brine prior to the curing operation and are relatively soft at the time they are subjected to the cure. During the curing operation there is a tendency for these soft pork sides to wrinkle and shrink, particularly along the teat side. Also the end of the pork side next to the shoulder is usually longer than the belly side, and various means have been devised attempting to square up such an irregular side of pork.

None of these attempts have been particularly successful, however, inasmuch as no rigid mechanical means has been devised for forcing and stretching the pork side into the exact shape and size desired and then holding it rigid in such position during the curing operation, which rigid holding precludes the forming of wrinkles as the bacon side shrinks.

In the construction shown in the drawing a relatively wide pork side 10 which may be as much as 11 or 12 inches in width is forced down to the bottom of a sloping sided trough 11 to the position shown in full lines in Fig. 2. The bottom of the trough is preferably approximately 9 inches in width and therefore the soft pork side when forced down to the bottom of the trough is wrinkled during the compressing of it.

In some instances it is preferable to remove the skin from the side of pork before placing it in the trough and subjecting it to the stretching operation, and in other instances the skin is left on, and when this is done the side is

preferably placed in the trough with the skin surface up.

My improved stretcher comprises a pair of rigid cross heads 12 and 13, each of which is provided with a plurality of impaling tines 14 and 15 respectively which are adapted to be thrust into the respectively opposite ends of the pork side 10.

The cross head 12 near its medial part is provided with a laterally rigid connecting bar 16 of U-shape cross-section, securely attached thereto by rivets, or the like, 17 at one end of the bar. The bar 16 comprises parallel spaced side walls and a connecting web 16a. The opposite end of the bar 16 is provided with a transverse pin 18 which passes through the opposite parallel sides of the U-shaped section and is securely riveted thereto.

The cross head 13, near its medial part, has a sleeve member 19 rigidly secured thereto as by rivets 20 which is adapted to slidably and telescopically receive one end of a laterally rigid connecting bar 21. The bar 21 is provided with upstanding spaced parallel lugs 22 and 23 which are drilled in alignment to receive a pivot pin 24 upon which is pivoted one end of a lever 25.

Means are provided for connecting the lever 25 to the sleeve 19 so that movement of the lever will slide the sleeve 19 and cross head 13 with respect to the bar 21 and comprises a pair of links 26 and 27, one end of each of which is pivoted at 28 to the lever 25, and the other end of each of which is pivoted at 29 to an upstanding lug on the sleeve 19. The lever 25 and links 26 and 27 are so formed, shaped and arranged as to have a toggle action when swung from the position shown in Fig. 3 of the drawing to the position shown in Figs. 4 and 6 of the drawing, whereby the toggle action will tend to lock the sleeve 19 and its cross head in extended position when subjected to tension which tends to slide the sleeve inwardly on its bar 21.

The lever 25 is extended beyond its toggle link connections and provided with a hook or eye end 30 by which the stretcher may be hung up during the curing operation. The middle of the hook or eye 30 is positioned along the longitudinal center line of the meat stretcher so that the apparatus will hang perpendicularly when suspended on a hook or nail.

The connecting bar 21 extends a considerable distance beyond the lugs 23 and 24 and is preferably of T-shaped cross-section to give it lateral rigidity. The web portion 31 of the T-bar section 55 is adapted to fit between the side walls of the U-shaped connecting bar 16, as shown more clearly in Fig. 5 of the drawing, with the flange portion 32 resting on the upper edges of the side walls.

60 The web 31 is provided with a plurality of longitudinally spaced bayonet slots 33, any one of which is adapted to receive the pin 18 rigidly mounted in the end of the connecting bar 16, and the lower web portion 16a of the bar 16 is 65 cut away beneath the pin 18 as shown at 16b, so that the connecting bar 21 may have limited pivotal movement, as shown in Fig. 3 of the drawing, when the pin 18 is engaged in any one of the slots 33.

70 Means are provided for locking the connecting bar 21 against pivotal movement about the pin 18 when the bar 21 is in prolongation of the bar 16, as shown in Figs. 4, 5 and 6 of the drawing, and comprise a spring finger 34, one end of which 75 is mounted in a lug or boss 35 on the side of the

bar 16, and the other end of which is curved outwardly away from the bar and then inwardly at right angles to its base supporting end with the free end passing through a slot 36 formed in one side wall of the bar 16. The inner free end of 5 the spring finger is positioned to engage in one of the bayonet slots 33 next adjacent to the slot in which the pin 18 is engaged.

In the modification shown in Fig. 7 of the drawing the sleeve 19 is provided with a pair of oppositely extending transversely disposed lugs 37 and 38 in which are rigidly mounted spring guiding rods 39 and 40 respectively, the free ends of which are adapted to slidably pass through openings formed in transversely disposed lugs 41 and 42 which are formed on the connecting bar 21. A helical compression spring 43, surrounding the rod 39, is interposed between the lugs 37 and 41, and a similar helical compression spring 44 surrounds the rod 40 and is interposed between the lugs 38 and 42.

In the operation of the apparatus and practice of the method herein disclosed the pork side 10, which may be 11 or 12 inches in width and which has been softened by soaking in brine solution, is 25 placed in the sloping-sided trough 11 and forced down to the bottom thereof, thus being compressed to a width of approximately 9 inches.

The stretching apparatus, comprising the cross heads with their connecting bars, is then affixed 30 to the opposite ends of the pork side by thrusting the impaling tines 14 and 15 down into the pork side close to the ends of the meat, and the two connecting rods joined, as shown in Fig. 3 of the drawing. It will be noticed that the pin 18 35 has been entered in one of the notches 33 in such manner that the distance between the cross heads 12 and 13 is considerably less than the sum of the lengths of the connected parts of the bars 16 and 21 between the pin 18 and heads 12 and 13, and the lever 25 is in such position that the sleeve 19 is slid fully on to the end of the connecting bar 21.

The operator then forces the upstanding end of the connecting bar 21 down into the slot of the U bar 16, as shown in Fig. 4 of the drawing, 45 which operation causes the pork side to be initially stretched. At this time the locking finger 34 is engaged in one of the bayonet slots adjacent to that in which the pivot pin 18 is engaged, and thus the two connecting bars are locked in prolongation. The eye or hooked end 30 of the lever 25 is then grasped by the operator and swung to the position shown in Figs. 4 and 6 of the drawing, 50 which action through leverage forces the toggle linkage to move the sleeve 19 outwardly with great force and thereupon further and finally stretch the pork side. Thereafter the pork side with the stretcher affixed thereto is removed from the trough 11 and hung up to cure into 55 bacon.

In the event one end of the pork side is not at right angles to the side edges, as shown in full lines in Fig. 9, one of the cross heads is first affixed to this end of the pork side with the cross head 65 substantially parallel to the angled side, and then the shank of the stretcher is swung over so as to be parallel to the longitudinal center line, whereupon the opposite cross head has its teeth thrust into the squared up end in the usual manner. This will cause greater stretching on the short side edge of the slab, and the final product will be squared up in rectangular form, as shown in dotted lines in Fig. 9.

In using the modification shown in Fig. 7 of 75

the drawing, the procedure is substantially the same as that described for the preferred embodiment, except that when the stretcher is forced down from the position shown in Fig. 3 to that shown in Fig. 4 of the drawing, the helical compression springs 43 and 44 are compressed. Thereafter the springs exert a constant stretching action on the soft meat until curing has progressed to the point of resisting further action of the springs.

It is to be observed that the cross heads 12 and 13 which carry the impaling tines 14 and 15 respectively are interconnected by laterally rigid connecting bars which maintain substantial parallelism between the cross heads at all times and thereby positively insure that the slab of bacon when finally cured will have opposite ends which are substantially parallel, and that the bacon side will be squared up into flat rectangular form.

In compressing the soft pork side in the sloping sided trough 11, it will, of course, slightly wrinkle transversely, but during the stretching operation these wrinkles will be entirely pulled out, so that the finished and cured slab will have a flat, plane surface free of wrinkles.

Although but one specific embodiment of this invention and one modification thereof have been herein shown and described, it will be understood that numerous details of the constructions shown may be altered or omitted without departing from the spirit of this invention, as defined by the following claims.

I claim:

1. A pork side stretcher comprising a pair of spaced substantially parallel cross heads, tines on said cross heads adapted to engage the ends of a pork side and laterally rigid connecting means attached to said cross heads for maintaining substantial parallelism therebetween and for forcing said cross heads apart to stretch the length of a pork side engaged by said tines, said connecting means including yielding means for exerting a constant stretching action on the pork side.

2. A pork side stretcher comprising a pair of spaced substantially parallel cross heads, tines on said cross heads adapted to engage the ends of a pork side, a bar on each of said cross heads, means for connecting said bars in substantial prolongation at spaced intervals to vary the distance between said cross heads, one of said bars having a plurality of notches therein, a pin on the other of said bars for engaging in any selected one of said notches whereby said bars may have pivotal action about said pin, and means

for locking said bars in substantial prolongation.

3. A pork side stretcher comprising a pair of spaced substantially parallel cross heads, tines on said cross heads adapted to engage the ends of a pork side, a bar on each of said cross heads, means for connecting said bars in substantial prolongation at spaced intervals to vary the distance between said cross heads, one of said bars having a plurality of notches therein, a pin on the other of said bars for engaging in any selected one of said notches whereby said bars may have pivotal action about said pin, and a spring finger on said last mentioned bar for engaging in another of said notches for locking said bars in substantial prolongation.

4. A pork side stretcher comprising a pair of spaced substantially parallel cross heads, tines on said cross heads adapted to engage the ends of a pork side, a bar on each of said cross heads, means for connecting said bars in substantial prolongation at spaced intervals to vary the distance between said cross heads, one of said bars being telescopically extensible, a lever pivoted to one member of said telescopic bar, and a link pivotally connecting said lever to the other member of said bar, said lever and link being arranged to extend the over-all length of said bar when said lever is moved to one position and form a toggle action lock when so moved.

5. A pork side stretcher comprising a pair of spaced substantially parallel cross heads, tines on said cross heads adapted to engage the ends of a pork side, a bar on each of said cross heads, means for connecting said bars in substantial prolongation at spaced intervals to vary the distance between said cross heads, one of said bars being telescopically extensible, a lever pivoted to one member of said telescopic bar, and a link pivotally connecting said lever to the other member of said bar, said lever and link being arranged to extend the over-all length of said bar when said lever is moved to one position and form a toggle action lock when so moved, the outer end of said lever being formed and shaped so as to be adapted to hang up said stretcher thereby.

6. A pork side stretcher comprising a pair of spaced substantially parallel cross heads, tines on said cross heads adapted to engage the ends of a pork side, a bar connecting the said cross heads, said bar being extensible in length, means for extending the length of said bar, and yielding means interposed in said bar whereby extension of said bar against yielding resistance will place said yielding means under tension.

HARRY F. LEE.
